FLOW-DISTRIBUTING DEVICE

Harry B. Cannon, P.O. Box 2432, Lakeland, Fla.
Filed July 15, 1960, Ser. No. 43,233

11 Claims. (Cl. 137—262)

This invention relates to a device for distributing flow from a single inlet to a number of outlets and more particularly relates to such a device for distributing a flow of slurry.

In processing a liquid slurry incorporating abrasive particles, it is often necessary to distribute the slurry flowing from a single outlet into a number of effluent streams. Such a need for distribution often occurs in apparatus for separating a slurry including mixtures of different particles into its constituent components, as for example, described in U.S. Letters Patent 2,902,154 issued to this same inventor. In that patent a circular trough distributes a slurry fed from a spoke-like array of inlet pipes to a similar disposed array of a larger number of troughs.

An object of this invention is to provide a simple and economical and efficient structure for a flow-distributing device through which the flow is subject to visual surveillance and clearance without interrupting operation.

Another object is to provide such a structure which is simply and economically installed and assembled upon a slurry-separating apparatus.

In accordance with this invention a highly effective flow-distributing device incorporates an uncovered receptacle made of wear-resistant material. A supply pipe is inserted into one side of this receptacle and a number of outlet conduits discharge from it. A splash-suppressing structure mounted within the receptacle in line with the flow from the supply pipe prevents splashing through the open top of the receptacle which facilitates visual surveillance and clearing without interruption of service. A remarkably effective form of such splash-suppressing means includes a number of spaced ribs which may be horizontally oriented and inversely stepped.

Novel features and advantages of the present invention will become apparent to one skilled in the art from a reading of the following description in conjunction with the accompanying drawings wherein similar reference characters refer to similar parts and in which:

FIG. 1 is a plan view of a slurry-separating apparatus incorporating one embodiment of this invention;

FIG. 2 is a view in elevation partially in cross section of the apparatus shown in FIG. 1;

FIG. 3 is a plan view of the flow distributing receptacle shown in FIGS. 1 and 2;

FIG. 4 is a view in elevation partially broken away of the receptacle shown in FIG. 3;

FIG. 5 is a cross sectional view taken through FIG. 4 along the line 5—5;

FIG. 6 is a plan view of another embodiment of this invention;

FIG. 7 is a view in elevation of the embodiment shown in FIG. 6 and

FIG. 8 is a cross sectional view taken through FIG. 7 along the line 8—8.

In FIGS. 1 and 2 is shown a separating apparatus 10 which is generally similar to the apparatus shown in U.S. Letters Patent 2,902,154 issued to the same inventor. This apparatus is used for separating a slurry incorporating granular mixtures into its constituent components, and the slurry stored in tank 12 is accordingly distributed through a spoke-like array of supply pipes or conduits 14 and distributing device 16 to a spoke-like array of a larger number of troughs 18, which in turn feed an inwardly directed array of separating convergent troughs 20. This present invention resides in a structure for and means

2

of supporting flow-distributing elements 16, which differ from the circular trough shown in the aforementioned patent for performing a similar function. However, other portions of separating apparatus 10 are generally similar to that shown in the aforementioned patent, and are therefore not described herein in detail.

Referring to FIGS. 3-5 which illustrate details of receptacle 16 in conjunction with FIGS. 1 and 2, it is apparent that receptacles 16 are uncovered to have open tops 21 for facilitating visual surveillance and clearance without interruption of service. Receptacles 16 are generally rectangular in cross section, and inlet pipes 14 extend through slots 22 in one of their longer sides. These receptacles are made, for example, of a somewhat flexible wear-resistant material such as rubber; and this makes the relatively thin internal flange 24 left within slots 22 elastic enough to snugly embrace the sides of supply pipe 14 to form an effective seal about it. Where the liquid slurry being handled incorporates oils or similar corrosive agents receptacles 16 may be made of an oil resistant rubber such as neoprene. Furthermore, these receptacles may be made of a wide variety of materials to suitably resist deterioration by the type of liquid or slurry being handled.

Each receptacle 16 also includes a pair of outlet openings 26 which are for example formed in their bottoms. The lower portion 28 of the inner walls of receptacles 16 slopes towards the conical entrances 30 to outlets 26 to help prevent clogging.

A splash-suppressing means 32 is mounted within receptacles 16 in line with the flow from supply pipes 14 which includes, for example, a number of horizontal spaced ribs 34. These ribs are approximately twice as long as the effective diameter of the inlet conduit, and project at unequal distances with the upper rib extending almost to the center of the receptacle, and the lower rib of the three illustrated extending only a slight distance into the receptacle. These ribs may, therefore, be considered inversely stepped. The spaces 36 between ribs 34 are for example substantially equal to the thickness of ribs 34, however, these ribs may be made much thinner than those illustrated and still perform effectively as long as they substantially cover the stream of flow discharging from inlet pipe 14. Flow-suppressing element 32 is for example replaceably mounted within wall 38 by insertion of its dove-tailed wall 40 within a corresponding dove-tailed slot 42 cut within receptacle wall 38. Splash suppressor 32 may therefore be easily replaced when this becomes necessary due to wear or damage.

As shown in FIGS. 1 and 2 receptacles 16 are mounted upon apparatus 10 by resting their lower sloped surfaces 44 upon the sloped upper surfaces 46 of troughs 18. Furthermore, receptacles 16 are anchored to a circular ring 48 which is secured to strips 50 extending between angular rings 52 and the upper inwardly turned edge 54 surrounding the outer ends of convergent separating troughs 20. Ring 48 is accordingly secured to strips 50 by vertical bars 56 which are provided in sufficient number to adequately support ring 48. Additional security is provided by attaching open loops 58 which surround receptacles 16 to ring 48 by looping their hooked ends 60 about them. Loops 58 are for example made of a substantially rigid material such as strip steel or brass which is formed as indicated to encompass receptacles 16 and be hooked about ring 48.

In FIGS. 6-8 is shown another form of receptacle designated 16A which incorporate a pair of outlets 26A in its side walls 62A instead of its bottom. Outlets 26A incorporate tubular sleeves 64A made together with the rest of receptacle 16A, for example, of a resilient material such as neoprene to permit them to snugly embrace and seal about the ends of discharge tubes 66A inserted with-

in tubular sleeves 64A. Flow-distributing receptacles 16A are in most other respects similar to flow-distributing receptacles 16, and in these common aspects will not be specifically described. However, the bottom wall 68A of receptacle 16A is flat which eliminates the sloped entrances to outlets 26 of receptacle 16.

Receptacles 16 and 16A both permit constant visual surveillance of the flow through them through their uncovered tops 21 and 31A. Splash-suppressing elements 32 and 32A are both amazingly effective in preventing undue splashing despite the proximity of these elements to these open tops. Ribs 34A might be made thinner than those shown and still be operative. However, any thinning in section decreases their wear resistance which is highly important in distributing a slurry incorporating highly abrasive particles. Furthermore, the ability of receptacles 16 to operate without unduly splashing of slurry out of them permits them to be cleared as well as closely watched without interruption of service which is highly important in handling a slurry which is susceptible to blockages in flow.

What is claimed is:

1. A flow-distributing device comprising a receptacle made of wear-resistant material having an uncovered top, one side of said receptacle including an opening for inserting an inlet conduit into said receptacle, a number of outlet conduits upon said receptacle, a splash-suppressing means mounted upon a side of said receptacle opposite said side through which said inlet conduit extends, said splash-suppressing means comprising a plurality of substantially parallel spaced ribs having sides and relatively shorter edges extending from said side of said receptacle substantially directly opposite said inlet opening toward the interior of said receptacle, and said sides of said ribs being disposed substantially in line with the path of the flow discharged from said inlet conduit whereby said flow from said inlet conduit impinges upon said edges of said ribs in the interior of said receptacle and enters in between said sides of said ribs to suppress splashing of said flow through said uncovered top which facilitates visual surveillance.

2. A flow-distributing device as set forth in claim 1 wherein said spaced ribs are horizontally oriented and inversely stepped.

3. A flow-distributing device as set forth in claim 2 wherein said inlet opening is arcuate, said ribs being approximately twice as long as the effective diameter of the said inlet conduit in said arcuate opening with the spaces between said ribs being substantially equal to the thickness of said ribs.

4. A flow-distributing device as set forth in claim 2 wherein said ribs are formed upon a removable insert, and detachable means are provided for securing said insert to said side for facilitating the replacement of said ribs.

5. A flow-distributing device as set forth in claim 1,

wherein a pair of said outlet conduits are formed in the bottom wall of said receptacle.

5 6. A flow-distributing device as set forth in claim 5 wherein said bottom wall is sloped to guide the flow smoothly into said outlet conduits.

7. A flow-distributing device as set forth in claim 6 wherein said bottom wall incorporates conical entrances into said outlet conduits.

10 8. A flow-distributing device as set forth in claim 1 wherein a pair of said outlet conduits are provided with said outlet conduits extending from opposite sides of said receptacle.

9. A flow-distributing device as set forth in claim 1 wherein said opening for said inlet conduit includes an internal flange made of resilient material which fits closely about said inlet conduit to seal it within said side.

15 10. A flow-distributing structure for distributing slurry from a number of supply conduits to a greater number of sloping troughs comprising receptacles having uncovered tops, said receptacles straddling over said troughs, each of said receptacles straddling over at least two of said troughs, one wall of each of said receptacles including an opening through which one of said inlet conduits extends, outlet conduits formed in the bottoms of said receptacles over each of said troughs, and a splash-suppressing element mounted within said receptacles in the line of flow of said slurry discharged from said inlet conduits, said splash-suppressing means comprising spaced ribs mounted upon the side of said receptacles opposite said opening extending across the path of flow discharged from said inlet conduits, said troughs and said inlet conduits being disposed in a spoke-like array, said receptacles each including a pair of outlet conduits, a supporting ring mounted over said troughs, the bottoms of said receptacles being sloped to correspond with the slope of the upper surfaces of said troughs for supporting said receptacles in an upright position above said troughs, and brackets attaching said receptacles to said ring for securing them in position.

20 11. A flow-distributing element as set forth in claim 10 wherein said brackets comprise open loops of substantially rigid material which encompass three sides of said receptacles, and the ends of said open loops being hooked about said ring.
